UNITED STATES PATENT OFFICE.

RAY T. BABBITT, OF PETOSKEY, MICHIGAN.

FOOT-POWER-OPERATED VEHICLE.

1,412,331.

Specification of Letters Patent. Patented Apr. 11, 1922.

Application filed June 14, 1921. Serial No. 477,544.

To all whom it may concern:

Be it known that I, RAY T. BABBITT, a citizen of the United States, residing at Petoskey, in the county of Emmett and State 5 of Michigan, have invented certain new and useful Improvements in Foot-Power-Operated Vehicles, of which the following is a specification.

This invention relates to toy vehicles and 10 the primary object of the invention is to provide an improved occupant propelled vehicle embodying a novel propelling means constructed so that a young child can operate the same with ease and without practice or 15 instructions, said operating means eliminating the employment of cranks, and connecting rods, in which a certain stroke at a certain timed interval is necessary for the effective operation thereof.

20 Another object of the invention is to provide a novel foot operated means for propelling toy vehicles, in which any desired length stroke can be given, without adjusting, for propelling the vehicle, the said 25 means including an actuating drum and ratchet members operatively connected to the drive axle and with the drum.

A further object of the invention is to provide a vehicle having a body constructed to 30 simulate the appearance of an animal, preferably a horse, the horse being provided with stirrups, which are adapted to receive the feet of the child and which are utilized for operating the propelling means.

35 A still further object of the invention is to provide a novel occupant propelled vehicle of the above character, which will present a pleasing and attractive appearance and which is durable and efficient in use, and 40 which can be placed upon the market at a reasonable cost.

With these and other objects in view, the invention consists in the novel construction, arrangement and formation of parts, as will 45 be hereinafter more specifically described, claimed and illustrated in the accompanying drawings, forming a part of this specification, in which drawings:

Figure 1 is a side elevation of the improved 50 toy vehicle.

Fig. 2 is a transverse section through the same taken on the line 2—2 of Figure 1.

Fig. 3 is a view similar to Figure 1 showing parts of the device in longitudinal section.

Fig. 4 is an enlarged fragmentary transverse section through a portion of the vehicle showing the means of mounting the propelling pulleys and ratchets on the drive axle.

60

Referring to the drawings in detail, where in similar reference characters designate corresponding parts throughout the several views, the letter A indicates the body of the vehicle, B the steering mechanism for the 65 vehicle, and C the operating means therefor.

The body A of the vehicle can be of any preferred character, but it is preferred that the same be constructed and shaped to simulate the appearance of an animal. As shown the body A is shaped to simulate the appearance of a horse and the rear legs 5 thereof are provided with bearings 6 for receiving the drive axle 7 which has keyed or otherwise secured thereon the drive ground engaging wheels 8. These wheels 8 may be of any preferred character, and as shown, the same are of the wire wheel type and are provided with rubber tires 8'.

70

80

The steering mechanism B is carried by the front portion of the body A, which is bored vertically at the longitudinal center thereof for rotatably receiving the steering post 10. Any suitable type of bearing can 85 be carried by the body for rotatably receiving the steering post 10 and suitable means may be provided whereby shifting movement of the steering gear will be prevented. The lower end of the post 10 is provided 90 with a fork 11 which rotatably receives the axle 12 on which is mounted the ground engaging steering wheel 13. This wheel 13 is constructed in the same manner as the rear drive wheels 8, only the diameter there- 95 of is smaller than the rear wheels. The upper end of the post 10 can be provided with any preferred steering mechanism and as shown, handle bars 14 are secured thereto. These handle bars 14 are arranged above 100 the body adjacent to the head of the horse. The body A at its lower surface is provided with an inwardly extending recess or chamber 16 for reception of a portion of the operating mechanism, which will now be described.

105

The propelling or operating means C comprises a longitudinally extending drum 20, the terminals of which are provided with bearing pins, 21 which are rotatably mount- 110.

ed in suitable hangers 22, which are fitted within the recess 16. This drum 20 is arranged at the longitudinal center of the body A preferably adjacent to the transverse center thereof and has wound about the same the web or drive strap 23. The terminals of the drive strap 23 are fitted with suitable stirrups or the like 24 for receiving the feet of the rider. Thus it can be seen that the drum can be operated, upon the pushing down of one stirrup and then the other. The drum of course is rotated in first one direction and then in the other. The drive axle 7 has rotatably mounted thereon for free movement a pair of pulley wheels 25 and 26, which are held in spaced relation, by means of a suitable spacing sleeve 27, which is arranged on the drive axle. The drive axle has keyed or otherwise secured thereto a pair of ratchet wheels 28 and 29 which are arranged adjacent to the rotatable pulley wheels 25 and 26. Each of the pulley wheels 25 and 26 is provided with pivoted dogs 30 which are adapted to engage the ratchet wheels when the pulley wheels are rotated in one direction, but which are adapted to slide over the ratchet teeth when the pulley wheels are rotated in a reversed direction. In order to drive the pulley wheels 25 and 26 from the drum 20 an endless cable 32 is provided. This cable 32 has its forward intermediate portion coiled around the drum as at 33 and extended outwardly from the opposite sides thereof. These runs of the rope which extend from the opposite side of the cable are trained around suitable guide pulleys 34 which may be secured to the side walls of the recess 16 formed in the body A. These runs of the cable are then coiled around the pulleys 25 and 26 and have their rear intermediate portion trained around a suitable central guide pulley 35, which can be secured in place in any preferred manner, and as shown a suitable hanger 36 is provided, which is secured to the rear wall of the recess 16.

In operation of the improved toy, the child sits upon the back of the horse and places his feet in the stirrups 24, and then pushes first down on one stirrup and then down on the other. This rotates the drum, first in one direction, and then in the other. It can be seen that when the drum is rotated in one direction a pull will be exerted on one run of the cable or one side of the body and a slack on the other run on the other side of the body. The run on which the pull is being exerted will rotate this pulley wheel in a counter clockwise direction, and the dog 30 will catch the ratchet wheel 28 thus rotating the drive axle 7 in a counter clockwise direction and move the vehicle forward. The other pulley wheel will be rotated in a reverse direction and its dog 30 will slide over

the other ratchet wheel. Upon the reverse movement of the drum, the other pulley wheel is rotated in a counter clockwise direction which drives the drive axle 7 while the other pulley wheel is rotated in a clockwise direction and its dogs slide over its ratchet wheel and thus does not impart movement to the axle. By this construction it can be seen that irrespective of the kind or length of the stroke of the stirrups, the drive axle 7 will always be rotated in a counter-clockwise direction to drive the vehicle forward. This mechanism makes the vehicle easy to operate by the young children, who fail to operate vehicles driven by pedals and the like, in which the stroke has to be of a certain length and at a certain time.

Changes in details may be made without departing from the spirit or scope of this invention.

I claim:

1. In an occupant propelled vehicle, a body constructed to simulate the appearance of an animal having a recess formed in the central portion thereof, a steering wheel carried by the forward portion of the body, a drive axle carried by the rear end of the body, drive wheels secured to the drive axle, a longitudinally extending drum arranged in the recess, hangers secured in the recess rotatably supporting the drum, a flexible strip coiled about the drum, feet receiving members secured to the terminals of the strip, drive pulleys rotatably mounted upon the drive axle, ratchet wheels secured to the axle adjacent to the pulleys, pivoted dogs carried by the pulleys arranged to engage the ratchets upon movement thereof in one direction, guide pulleys arranged in the recess, and an endless operating cable trained about the guide pulleys and the drive pulleys, and about said drum.

2. An operating means for vehicles comprising a rotatable drum, a drive strip coiled about the drum, feet receiving members secured to the terminals of the strips, guide pulleys arranged on each side of the drum, a central guide pulley arranged in rear of the first mentioned guide pulleys, a drive axle, a pair of spaced drive pulleys rotatably mounted upon the drive axle, ratchet wheels secured to the drive axle, pivoted dogs carried by the drive pulleys arranged to engage the teeth of the ratchet wheels upon movement of the drive pulley wheels in one direction, an endless drive cable having its forward intermediate portion coiled about the drive drum and having its rear intermediate portion trained about the centrally disposed guide pulley, the intermediate portions of the endless drive cable being trained about the first mentioned guide pulleys and about said drive pulleys.

RAY T. BABBITT.
